UNITED STATES PATENT OFFICE.

WILLIAM E. FOWLER, JR., OF MOUNT LEBANON, PENNSYLVANIA, ASSIGNOR TO DAVIS BRAKE BEAM COMPANY, OF JOHNSTOWN, PENNSYLVANIA, A CORPORATION OF PENNSYLVANIA.

SECURING BRAKE-BEAM SUPPORT TO TRUCKS.

Application filed May 15, 1924. Serial No. 713,561.

To all whom it may concern:

Be it known that I, WILLIAM E. FOWLER, Jr., residing at Mount Lebanon, in the county of Allegheny and State of Pennsylvania, a citizen of the United States, have invented or discovered certain new and useful Improvements in Securing Brake-Beam Supports to Trucks, of which improvements the following is a specification.

The invention described herein relates to the class or type of devices known in the art as brake beam supports, which are used as auxiliaries to the hangers to maintain the brake shoe whether in contact with the tread of the wheel or in normal position in proper concentric position relative to the wheel and to ensure the proper application of the brake shoes regardless within limits of the diameter of the wheels. These supports consist of one or two spring bars or rails, dependent upon whether the brake beam is to be supported at two points in addition to the usual hangers, and a shoe or shoes interposed between the brake beam and the rail or rails. Preferably and in most cases the rail or rails are secured to the spring plank of the truck and on account of the position of the spring plank relative to other parts of the truck, difficulty is encountered in so attaching the rails which extend on both sides of the spring plank in such manner as will permit of the easy removal and replacement of the rails when repairs are necessary.

The invention described herein relates to certain improvements in the manner of attaching the rails described and claimed in an application filed February 28, 1924, by Broderick Haskell, Serial No. 695,795, which consists, generally stated, in forming the rail with a portion adapted to be passed through an opening in the spring plank and providing means whereby the portion projecting through the opening is prevented from accidental withdrawal. The improvement is hereinafter more fully described and claimed.

In the accompanying drawings forming a part of this specification, Fig. 1 is a plan view showing a portion of the spring plank of a truck and a supporting rail secured to the plank in the manner claimed herein; Figs. 2 and 3 are sectional views on planes indicated respectively by the lines II-II

and III-III, Fig. 1; Figs. 4 and 5 are views similar to Figs. 1 and 2 illustrating a modification of the improvement; Fig. 6 is a view similar to Fig. 5 illustrating a modification of the improvement; and Fig. 7 is a sectional view on a plane indicated by the line VII-VII.

In the practice of the invention the supporting rail extends across the spring plank 1 and projects a sufficient distance on each side of the spring plank to underlie the tension members 2 of the brake beam. The end 65 portions 3 of the rail are so bent as to have an upward inclination when the rail is secured to the truck and on these portions 3 are movably mounted blocks or shoes 4 having seats 5 for the tension members 2. The 70 shoes are held as against accidental movement off of the rails by shoulders 3^a which are conveniently formed by headed rivets, as shown.

The intermediate portion of the rail is so 75 bent that the rail will bear on the plank only at points adjacent to the edges of the plank as indicated at 6, such bearing portions having sufficient length to remain in contact with the plank during any permissible longitudinal movements of the rail. The means employed for connecting the rail to the plank at a point intermediate the bearings 6 are so constructed that the portions intermediate the seats must be deflected 80 from normal before such connection can be effected. In the construction shown herein the means employed to attach the rail to the plank consists of a loop or U-shaped portion 7 oppositely inclined resilient portions 8 extending from the loop to the bearings 6, said loop being passed through an opening in the spring plank and held in position by a key or pin.

By reference to Fig. 2 it will be seen that 95 the portions 8 will when the bearings 6 contact with the plank, be inclined away from the plank and the loop is made of such a height that the portions 8 must be deflected from normal in order that the loop may pass 100 through the opening 9 in the spring plank sufficiently far for passing a locking pin 10 through the loop. This pin is made of such a length that its ends will bear on the upper face of the spring plank on opposite sides 105 of the opening 9. The pin is provided with

shoulders 11 adapted to bear against opposite edges of the opening 9 to prevent its longitudinal movement out of the loop. The opening through the spring plank is made of such a width relative to the length of the bearings 6 of the rail on the plank that the loop 7 will contact with the sides of the opening in the plank and prevent such longitudinal movement of the rail as will move the bearings 6 out of contact with the plank. It is characteristic of the described construction that the rail has three points of bearing on the spring plank, i. e., the bearings 6 on one side of the plank and the locking pin 10 on the opposite side. The rail or at least the portions of the rail intermediate the bearings 6 are resilient.

As is well known in the art, the spring plank may be formed by channel bars 1 as shown in Figs. 1, 2 and 3, or by spaced angle bars 1^a, as shown in Figs. 4 and 5. When the plank is formed of angle bars the supporting rail is attached to a plate 12 extending across the gap between the angle bars and riveted or otherwise secured thereto.

When applying the support rail above the spring plank, which can be readily done when the plank is formed with narrow or low flanges, the portions of rail intermediate the inclined portions carrying the shoes and the loop 7^a are made straight as shown in Figs. 7 and 6, the low flanges 13 of the plank 1^b operating to perform the function of the bearings 6 in the construction shown in Figs. 1 to 3, of so supporting the middle portion of the rail in which the loop is located in such position that portions must be deflected in order to permit of the rail being locked to the plank.

By reference to Figs. 1 and 2 it will be seen that by the employment of a shoe having an open-topped seat or saddle, the brake beam can be placed or replaced in position without changing the position of the supporting rail which carries the shoe, and also that the supporting rail and shoe can be placed in position without changing the connection of the brake beam with the truck and without changing either the shape of the shoe or its manner of connection with the supporting rail.

It is characteristic of the construction shown and described herein that as the shoes are freely movable along the supporting rails and that the tension member can slide freely along the seats or saddles of the shoes, the brake beam is free to move at all times in directions at an angle to and parallel with the supporting rails and thus automatically adjust itself to operative position.

I claim herein as my invention:

1. The combination of a truck element and a supporting rail having spaced bearings on one side of the truck element, and a

bearing on the opposite side of the truck element, the latter bearing being intermediate of and spaced from the other bearings.

2. The combination of a truck element and a supporting rail having a point intermediate its ends connected to the truck element and having points spaced from such point of connection bearing resiliently on the truck element.

3. The combination of a truck element provided with an opening and a supporting rail having spaced points of bearing on one side of said element, an intermediate portion projecting through the opening in the truck element and means engaging the projecting portion and having a bearing on the truck element.

4. The combination of a truck element provided with an opening, a supporting rail having spaced points of bearing on one side of said element, the section of the rail between such points of bearing being resilient, said resilient section being provided with a portion projecting through the opening in the truck element and means engaging the projecting portion and having a bearing on the truck element.

5. The combination of a truck element provided with an opening, a supporting rail having spaced points of bearing on one side of the said element and provided with a loop or U-shaped portion intermediate said points of bearing and projecting through the opening in said element, and a pin passing through the portion of the projecting element from the opening and bearing on the truck element.

6. The combination of a truck element provided with an opening, a supporting rail having spaced points of bearing on one side of said element provided with a loop or U-shaped portion intermediate said points of bearing and projecting through the opening in said element, the sections intermediate the spaced points of bearing being resilient, and a pin passing through the portion of the projecting element from the opening and bearing on the truck element.

7. The combination of a truck element provided with an opening, a supporting rail provided with a loop or U-shaped portion adapted to project through the opening in the truck element, and the portion on opposite sides of the loop being shaped to bear on the truck element at points distant from the opening therethrough, and a pin passing through the portion of the loop projecting through the opening and bearing on the truck element.

8. The combination of a spring plank, a supporting rail adapted to bear on the plank adjacent to its edges and having resilient portions extending downwardly from the points of bearing on the plank and a loop intermediate the inclined portions and

means engaging the loop and plank and thereby holding the rail in position on the plank.

9. The combination of a spring plank, a supporting rail adapted to bear on the plank adjacent to the edges thereof and resilient portions extending inwardly from the points of bearing of the rail on the plank and means for attaching an intermediate point of the resilient portion to the plank.

10. The combination of a truck element, a supporting rail secured to the truck element, a brake beam and a shoe, the brake beam being freely movable relative to the shoe and rail and the shoe slidable along the rail.

11. The combination of a truck element, a supporting rail secured to the truck element, a shoe movably mounted on said supporting rail and a brake beam so supported by the shoe as to be freely movable along the shoe.

12. The combination of a truck element, a supporting rail secured to the truck element, a brake beam and a shoe slidable along the supporting rail, the brake beam

being so supported by the shoe as to be freely movable longitudinally on the shoe and a stop for limiting the movement of the shoe along the rail.

13. The combination of a truck element, a supporting element, carried by the truck element, a brake beam and a shoe interposed between the portion of the brake beam and the supporting element and movable relative to each of said parts and provided with means adapted to prevent movements of the shoe transverse of said parts.

14. The combination of a truck element, a supporting element carried by the truck element, a shoe adapted to be shifted along the supporting element and having portions adapted to so engage said element as to be maintained in operative relation thereto, and a brake beam slidably carried and engaged by the shoe whereby the shoe may be shifted along the supporting element by the brake beam and the latter may move relative to the shoe.

In testimony whereof, I have hereunto set my hand.

WILLIAM E. FOWLER, JR.
